(57) **CLAIM**

The ornamental design for a baseball and bat display bed, as shown and described.

DESCRIPTION

FIG. 1 is a perspective representational view of the baseball and bat display bed;

FIG. 2 is a first end view, of the baseball and bat display bed;

FIG. 3 is a second end view of the baseball and bat display bed;

FIG. 4 is a first side view of the baseball and bat display bed, the second side view being substantially a mirror image thereof;

FIG. 5 is a top plan view of the baseball and bat display bed; and,

FIG. 6 is a bottom plan view of the baseball and bat display bed.

The broken lines are for environmental purposes only and form no part of the claimed design.
